UNITED STATES PATENT OFFICE.

CHARLES W. HART, OF TROY, NEW YORK, ASSIGNOR TO HARRIET A. HART,
OF SAME PLACE.

DESIGN FOR A SHEET-METAL CAN.

SPECIFICATION forming part of Design No. 26,364, dated December 1, 1896.

Application filed October 27, 1896. Serial No. 610,230. Term of patent 14 years.

To all whom it may concern:

Be it known that I, CHARLES W. HART, a citizen of the United States, residing at Troy, county of Rensselaer, and State of New York, 5 have invented and produced a new and original Design for a Sheet-Metal Can, of which the following is a specification, reference being had to the accompanying drawings, wherein—

10 Figure 1 is a view in perspective of my newly-designed can, and Fig. 2 is a vertical central section of the same.

15 The can comprises the circular bottom A, the base B, and the body C. The bottom comprises a flat circular surface of comparatively small diameter, and the body is of general cylindrical form, flaring slightly toward the top. The base flares widely from the bottom to its junction with the body. A bead 20 C' extends around the top of the can, and a

similar bead C² extends around the body along its line of junction with the base. A short distance below the top bead C' is a groove C³, which extends around the can-body.

25 The essential feature of the design is comprised in the flat circular bottom of comparatively small diameter, the widely-flaring base, and the slightly-flaring body of the can.

What I claim as new, and desire to secure 30 by Letters Patent, is—

The design for a sheet-metal can herein shown and described.

In testimony whereof I have hereunto set my hand this 19th day of October, 1896.

CHARLES W. HART.
